CLAIM

The ornamental design for a strip with flexible fibers, as shown and described.

DESCRIPTION

FIG. 1 is an exploded top plan view of a strip with flexible fibers; the reverse side being identical;

FIG. 2 is an enlarged detail view of area 2 circumscribed within FIG. 1;

FIG. 3 is an enlarged left side view thereof; and,

FIG. 4 is an enlarged view of the area between arrows 4-4 in FIG. 1.

The broken lines surrounding area 2 in FIG. 1 and along the edge of FIG. 2 denote the boundaries of the detail area and form no part of the claimed design.

All other broken lines in FIG. 1 denote the manner of assembly of the exploded sections of the strip with flexible fibers and form no part of the claimed design.
